DESIGN FOR AN ELECTRIC SADIRON

Russell I. Huffman, Dover, Ohio, assignor to
Knapp-Monarch Company, St. Louis, Mo., a
corporation of Delaware

Application April 15, 1947, Serial No. 138,412

Term of patent 14 years

(Cl. D49—6)

To all whom it may concern:

Be it known that I, Russell I. Huffman, a citizen of the United States, and a resident of Dover, in the county of Tuscarawas and State of Ohio, have invented a new, original, and ornamental Design for an Electric Sadiron, of which the following is a specification, reference being had to the accompanying drawing, forming part thereof:

Fig. 1 is a top plan view of an electric sadiron, showing my new design.

Fig. 2 is a side elevational view thereof.

Fig. 3 is a front elevational view thereof, and
Fig. 4 is a rear elevational view thereof.

I claim:

The ornamental design for an electric sadiron,
substantially as shown.

RUSSELL I. HUFFMAN.
